UNITED STATES PATENT OFFICE

2,413,270

MOVABLE ANVIL RIVETING MACHINE

Loyd A. Ward, Detroit, and Eben D. Taylor, Jackson, Mich., assignors to Tomkins-Johnson Company, Jackson, Mich., a corporation of Michigan

Original application February 28, 1938, Serial No. 192,946, now Patent No. 2,360,991, dated October 24, 1944. Divided and this application March 6, 1944, Serial No. 525,170

1 Claim. (Cl. 78—48)

1

This application is a division of our application Serial No. 192,946, filed February 28, 1938, now Patent No. 2,360,991, granted October 24, 1944, and relates to riveting machines and the like, and more particularly to such a machine having a movable anvil.

In riveting it is often desirable to dispose a rivet or other upsettable member in supported relation to an anvil so that the work may be disposed over the upsettable member and the upsettable member headed up. Numerous structures have been developed for automatically presenting an upsettable member in such a manner that the work may be placed over the same and the upsettable member immediately upset. Various difficulties have been met, such as the use of too many moving parts for economic manufacture or operation or the use of structures which do not rigidly support an upsettable member for receiving the work and being acted upon by the set. The present invention contemplates the use of a movable anvil which may be alternately moved from a position in alignment with the upsettable member feeding means to a position in co-operating relation with the set and back again.

An object of the invention is to provide a riveting machine or the like having an anvil which is laterally movable with respect to the set.

Another object of the invention is to provide a riveting machine or the like having a movable anvil arranged to clamp therein an upsettable member which presents the same beneath the set for being acted upon thereby.

A still further object of the invention is to provide a riveting machine or the like having an anvil moving from a station for presenting an upsettable member to the anvil, to a second station in operative relation with the rivet set, together with means controlled by the anvil moving means for controlling the feeding of the upsettable members to the anvil.

These and other objects will be apparent from the following specification when taken from the accompanying drawing, in which

Fig. 1 is a partial vertical section of the present invention.

Fig. 2 is a partial plan view of the invention disclosed in Fig. 1, and

Fig. 3 is a section on line III—III of Fig. 2.

In the form of the invention illustrated in the drawing, a laterally movable anvil 60 is slidably disposed on the base 61 and guided by overhanging members 62 secured to sides of the base 61. The anvil 60, as shown in Fig. 3, tapers upwardly to provide at the top a seat just wide enough to

2

receive an upsettable member 63. The upsettable member 63 is supported in position on the top of the anvil 60 by jaws 64. The jaws 64 are provided with shank portions 65, which are secured by screws 66 to blocks 67 secured to the anvil by screws 68. The spring metal shanks 65 are provided with a set, which urges the jaws 64 against the sides of the anvil 60 and at the same time against the upsettable member 63, which is disposed between the jaws 64. Leaf springs 69 are also secured by the screws 66 to the blocks 67 to reinforce the action of the shanks 65.

The anvil 60 is reciprocated by a rod 74, which is operated by a suitable power source but preferably by a piston and cylinder provided with controls such as disclosed in the patent issued to Robert C. Hoyt, No. 2,176,008, granted October 10, 1939. Leftward movement of the anvil 60, as viewed in Fig. 1, is limited by a shoulder 75 engaging with a plate 76 secured to the base 61.

Upsettable members are fed from a suitable hopper similar to the hopper 18 disclosed in our aforesaid application, Serial No. 192,946, to an inclined chute 77. Upsettable members in the chute 77 are held near the lower end thereof by a nose 78 comprising a portion of selector mechanism 79. The selector mechanism 79 comprises, in addition to the nose 78, a stop 80, and is slidably in a horizontal channel 81 in the inclined face of the supporting block 82.

It will be observed from Fig. 2 that the nose 78 and the stop 80 of the selector 79 overlie the chute 77, the latter being secured to the supporting block 82, while it is the lower portion of the selector 79 which is disposed in the channel 81.

The selector 79 is normally urged to the right, as viewed in Figs. 1 and 2, by a cantilever leaf spring 83 secured to a frame portion 84 and disposed in a slot 85 in the selector 79. Movement of the selector 79 to the left is provided by a stop 86 secured to and projecting upwardly from the rod 74. The free end of the spring 83 is disposed in the path of the stop 86 for engagement thereby when the anvil 60 is moved to the left to move the leaf spring 83 against the opposite side of the slot 85 and thus to move the selector 79 to the left.

As shown in Figs. 1 and 2, there is an upsettable member 63 on the anvil 60 in co-operating relation with the set 87 and another upsettable member at the extreme bottom of the chute 77, supported there by a stop 88 and by an extension 89 secured to the anvil 60 by screws 90. The anvil extension 89 in the form of a cantilever bar provides a seat for the upsettable member against

the stop 88. In this position the upsettable member is in the path of the clamping jaws 64.

After the work has been disposed over the upsettable member 63 on the anvil 60 and the set 87 has upset the upsettable member 63, the aforesaid control is manually actuated to move the anvil 60 to the right. As the anvil 60 moves to the right, the anvil extension 89 moves with it, the upsettable member at the bottom of the chute 77, sliding on its surface. The clamping jaws 64 are provided with guiding edges 91 and curved active portions 92, which engage the head of the upsettable member. Thus, as the anvil 60 is moved to the right, the upsettable member held by the stop 88 is guided by the edges 91 into position between the active portions 92 of the clamping jaws 64. When the anvil 60 has moved to its extreme right position and has received between the jaws 64 an upsettable member from the bottom of the chute 77, it is automatically returned by mechanism, such as disclosed in the aforesaid Hoyt patent, into co-operating relation with the set 87, carrying with it the upsettable member between the jaws 64.

When the anvil 60 is in its extreme right position, the stop 86 has moved away from the leaf spring 83, which in turn, due to its initial set, has moved the selector 79 to the right, moving the nose 78 away from the lowest upsettable member in the chute 77 and permitting the upsettable members to drop down the chute 77 against the stop 80, which has moved across the path of movement of the upsettable members in the chute 77. When the stop 86 again engages the free end of the leaf spring 83 on the return movement of the anvil 60 into co-operating relation with the set 87, the selector 79 is moved toward the left, projecting the nose 78 between the rivet clamping means and the stop 80 and the one next

to it. The nose 78 thus acts to stop downward movement of all the upsettable members in the chute 77 except the one that was immediately next the stop 80. As the nose 78 moves to the left, the stop 80 also moves to the left and permits the upsettable member which was next to it to slide down the chute 77 into position against the stop 88 and resting on the anvil extension 89 in position to be transferred to the top of the anvil 60 between the jaws 64 the next time the anvil 60 moves to the right.

As an example of a change that may be made, the selector 79 disclosed in Figs. 1 and 2 may be reversed so that an upsettable member is selected 15 from the chute 77 upon the movement of the anvil away from co-operating relation with the set rather than upon the movement of the anvil toward co-operating relation with the set, as is disclosed.

Having thus described our invention, what we desire to secure by Letters Patent and claim is:

A machine of the character described, comprising a laterally movable anvil having rivet clamping means associated therewith, said rivet 25 clamping means being movable with said anvil, a set, an extension from said anvil for upsettable members, means to dispose an upsettable member on said anvil extension, means including said anvil extension to support upsettable members 30 in the path of movement of said anvil and rivet clamping means, said rivet clamping means having means to guide an upsettable member disposed as aforesaid into clamping relation with said clamping means as said anvil and rivet 35 clamping means move laterally away from said set, and means to move said anvil and upsettable member into co-operating relation with said set.
